United States Patent

Des. 239,127
Patented Mar. 9, 1976

239,127

TOY VEHICLE

James R. Powers, Los Angeles, Calif., assignor to
Tomy Corporation, Long Beach, Calif.

Filed Aug. 14, 1974, Ser. No. 497,255

Term of patent 14 years

Int. Cl. D21—01

U.S. Cl. D34—15 AJ

FIG. 1.

FIG. 2.

FIG. 3.

FIG.4.

FIG.5.

FIG. 1 is a side elevational view of a toy vehicle showing my new design, the side opposite being substantially a mirror image;

FIG. 2 is a top plan view thereof;

FIG. 3 is a bottom plan view thereof;

FIG. 4 is a front elevational view thereof; and

FIG. 5 is a rear elevational view thereof.

I claim:

The ornamental design for a toy vehicle, as shown and described.
